COMBINATION MARINE RUNNING AND ANCHOR LIGHT

André Ullmo, University Heights, and Steven J. Jambor,
Cleveland, Ohio

Application October 20, 1955, Serial No. 38,489

Term of patent 3½ years

(Cl. D48—24)

Fig. 1

Fig. 3

Fig. 2

Fig. 4

Figure 1 is a top plan view of the combination marine running and anchor light, embodying our new design;

Figure 2 is a front elevational view of the same;

Figure 3 is a bottom plan view of the same; and

Figure 4 is a right end view thereof.

The running light lenses are lined for the colors red and green.

We claim:

The ornamental design for a combination marine running and anchor light, substantially as shown and described.
